2,900,101

FINISHED COVER FOR UNDERFLOOR JUNCTION BOX

Edward B. Clark, Milford, Conn., assignor to General Electric Company, a corporation of New York

Application September 30, 1957, Serial No. 687,329

2 Claims. (Cl. 220—3.4)

The present invention relates to underfloor wiring distribution systems and particularly to a finished floor cover that may be installed as part of a standard junction box connecting the intersecting runs of underfloor duct. Such junction boxes are sometimes called duct boxes, and are usually of heavy cast iron having a bottom wall, side walls and a top wall. The side walls contain duct-receiving openings, while the top wall includes a large hand-hole or access opening, usually circular in shape, so that the wires may be installed in the ducts.

Underfloor duct systems are widely used in large stores and office buildings of fireproof construction where the ducts are buried in the concrete floor. Each duct box has a handhole in its top wall that is closed by a removable floor cover and designed to lie flush with the concrete surface. Oftentimes it is desirable to cover the concrete with a finished flooring of wood, linoleum, or composition tile. Accordingly, it is necessary to provide a finished floor cover over the box that will likewise be flush with the finished flooring.

The principal object of this invention is to provide an underfloor duct box with a finished floor cover that will be flush with the finished flooring and also have means for protecting the edge of the finished flooring.

A further object of this invention is to provide a finished cover for a duct box of an underfloor wiring distribution system that incorporates the use of a novel trim ring for protecting the edge of the finished flooring where the flooring terminates adjacent the finished cover.

A still further object of this invention is to provide a finished cover of the class described with means for lifting the cover to gain access to the box.

The preferred embodiment of the present invention includes a finished cover that is inlaid with material similar to that of the finished flooring of the building. The top edge of the finished cover has a tapered side flange cooperating with a trim ring in which the cover is placed. The top inner edge of the trim ring is beveled or countersunk to receive the tapered flange of the finished cover and present a perfectly smooth surface extending over the several parts. The trim ring is placed on the concrete flooring and is centered over the floor cover of the duct box. The lower edge or base of the trim ring has an outer flange that is covered by the finished flooring as it is being laid. When the finished cover is removed, the trim ring is temporarily held in place by the finished flooring. However, when the finished cover is fastened down, the tapered side flange of the finished cover will securely hold the trim ring in place.

My invention will be better understood from the following description taken in connection with the accompanying drawing and its scope will be pointed out in the appended claims.

The single figure of the drawing is a perspective view of a typical floor construction shown in vertical cross-section through a duct box embodying my invention with the concrete fill and the finished flooring in place.

Referring in detail to the drawing, 10 designates a

2

portion of the top wall of a standard duct box having a handhole or access opening 11 that is defined by an upstanding flange 12. A leveling ring 13 is telescoped over the flange 12 and it has a continuous inner shelf or ledge 14 shown resting on the top surface of the flange. As is the general practice, the leveling ring 13 is vertically adjustable by means of elevating screws (not shown) that are threaded into the top wall 10 of the box. Hence, if the concrete fill 15 were poured in excess, it would be possible to raise the leveling ring 13 so that its top surface would be flush with the top of the concrete. Since this vertical adjustment is well known in this art, it is not deemed necessary to illustrate it in the drawing as it does not form part of the present invention.

An annular rubber gasket 17 is placed on the shelf 14 of the leveling ring and a heavy floor cover 18 is assembled within the leveling ring and seated on the gasket to form a sealed cover for the handhole. Several spaced lugs 20 extend inwardly of the shelf 14 and each contain a threaded opening 21 to receive a flat headed screw 22 extending through a suitable countersunk opening in the floor cover 18 to hold the cover in place. Since the screws 22 are within the inner diameter of the rubber gasket 17, the gasket may be made very simple without any clearance holes and the necessity of aligning the holes with the openings 21 in the leveling ring 13. It also should be noticed that the top surface of the floor cover 18 is slightly depressed below the upper surface of the leveling ring 13 and concrete fill 15, for reasons which will be explained hereinafter.

A finished flooring 25 such as hardwood flooring, linoleum or composition tile is often used over the concrete fill 15. This presents the problem of providing a removable cover for the duct box that will be flush with the top surface of the finished flooring. This has been solved in the following manner, with the inclusion of the finished floor cover 26 and a trim ring 27. The finished cover 26 is of dish shape with a bottom wall 28 and a continuous side wall 29. A boss 30 is located in the center of the bottom wall and it has an oversized threaded opening 31 for loosely receiving a flat headed screw 32 that is to be threaded into a central opening 36 of the floor cover 18. The purpose of the threaded opening 31 in the boss 30 is to permit the easy removal of the finished cover. This is accomplished by first removing the screw 32 and then threading a larger size screw (not shown) into the opening 31 thereby making it possible to lift the finished cover out of the floor.

The recessed part of the finished cover is inlaid as designated at 33 with a slug of material that will match the finished flooring 25 placed over the concrete fill 15. If the inlaid material 33 is of the same thickness as the finished flooring 25, which would be the usual case, it is necessary to depress the cover 18 below the top surface of the leveling ring 13 to allow for the thickness of the material of the bottom wall 28 of the finished cover, as is clearly shown in the drawing.

The trim ring 27 is seated on top of the leveling ring 13 and it is adapted to receive the finished cover 26 therein. It also overlies a portion of the concrete 15. The lower edge or base of the trim ring 27 has an outer flange 35 that is to be covered by the finished flooring 25. Accordingly, the steps taken to lay the finished flooring would be preceded by the positioning of the trim ring 27 over the leveling ring 13 and the fastening of the finished cover 26 to the floor cover 18. Then, the finished flooring 25 would be laid and trimmed carefully to fit snugly around the trim ring 27. Also, it should be noted that the top outer edge of the side wall 29 of the finished cover is provided with a tapered flange 37 that is tapered along its bottom surface outwardly from the side wall. Also, the top inner edge of the trim ring

27 is beveled or countersunk as at 38 to receive the tapered flange so that when the finished cover is fastened down, it will securely hold the trim ring in place.

Having described above my invention of a finished cover and trim ring of novel construction, it should be readily apparent that the resulting floor structure would be perfectly smooth, and the inner edge of the finished flooring would be well protected from abuse and permanent damage. Since the finished cover and trim ring produce a smooth top surface, it will be understood that the resulting floor would be safe for heavy pedestrian and truck traffic without fear of stumbling or damage to the appearance of the floor. Although I have chosen to illustrate my invention with the finished cover fastened indirectly to the leveling ring 13 through the medium of the floor cover 18, it should be readily apparent to those skilled in this art that the cover 18 could be completely eliminated and suitable screw means could be provided for the finished cover that would be threaded directly into the lugs 20 of the leveling ring 13.

Modification of this invention will occur to those skilled in this art and it is to be understood, therefore, that this invention is not limited to the particular embodiments disclosed but that it is intended to cover all modifications which are within the true spirit and scope of this invention.

What I claim as new and desire to secure by Letters Patent of the United States is:

1. An underfloor duct box comprising in combination an open top wall that is defined by an upstanding circular flange, a leveling ring centered over the said flange and having a top surface adapted to be flush with the top of a concrete slab, an inwardly directed ledge extending from the inner side of the leveling ring, a resilient gasket positioned on said ledge, and a metal cover plate seated on the gasket to close the top wall of the box, a trim ring seated on the leveling ring and having an outer flange at its lower end to overlie the concrete and be covered and held down by a finished flooring that will lie flush with the top surface of the trim ring, and a finished cover supported by the trim ring and over the
